Des. 229,308
Patented Nov. 20, 1973

229,308

FISHING LURE

Otto W. Hofacker, 3934 N. Broadmoor Ave.,
Covina, Calif. 91724

Filed Aug. 17, 1972, Ser. No. 281,333

Term of patent 14 years

Int. Cl. D22—05

U.S. Cl. D22—27

FIG. 1.

FIG. 4.

FIG. 2.

FIG. 5.

FIG. 3.

FIG. 1 is a side elevational view of a fishing lure, showing my new design;

FIG. 2 is a plan or top view thereof;

FIG. 3 is a bottom view thereof;

FIG. 4 is a front view thereof; and

FIG. 5 is a rear view thereof.

I claim:

The ornamental design for a fishing lure, as shown.
